John Barnes
ATTORNEY

UNITED STATES PATENT OFFICE.

THOMAS J. LAURENCE, OF DETROIT, MICHIGAN, ASSIGNEE TO CHRYSLER CORPORATION, OF HIGHLAND PARK, MICHIGAN, A CORPORATION OF DELAWARE.

HEAT-TREATING FURNACE.

Application filed June 25, 1927. Serial No. 201,531.

My invention relates to heat treating furnaces of the type wherein the pieces to be treated are continuously forced thru the furnace on trays or carriers.

5 In furnaces of this type the practice heretofore has been to carry the trays holding the piece to be treated, to the furnace door on a conveyor, and then to force the tray into the furnace and thru the same by the 10 tray or carrier immediately behind.

One of the objects of my invention is to improve on this method by providing a continuous track leading into the entrance of and thru the furnace. Therefore, in my 15 invention, there is no transference of carriers from a conveyor to the furnace floor, but a smooth continuous movement of the trays thru the furnace along the tracks.

In the treating of cylindrical objects such 20 as axles and cam shafts it is not good practice to lay them on a carrier and pass them thru a heat treating furnace because the shaft will be unequally heated, and therefore it is a further object of my invention 25 to provide means inside the furnace to lift the shaft from the carrier so that the carrier acts as a pusher and rolls the shaft thru the furnace on the means, shown as ridges thus insuring an even distribution of heat 30 around the entire circumference of the shaft, due to its rotation.

Other objects of my invention are to provide small disconnected carrying elements that require small entrance and exit openings 35 in the furnace walls so that the amount of heat allowed to escape thru these openings will be much less than in the case of other types of furnaces.

Another important object is to provide 40 means for conducting objectionable fumes from the tempering liquid into the furnace that they may be consumed by combustion. It is still further desirable to provide a 45 means for returning the carrying elements to the front end of the furnace that they may be used over again.

The above stated objects of my invention will be more fully understood from the following specification and drawings, in which:

50 Fig. 1 is a side view of a heat treating furnace, partly in section showing a loading table and a tempering tank.

Fig. 2 is a sectional view on line 2—2 of Fig. 1.

Fig. 3 is a perspective view of one form of carrying block.

I have shown a heat treating furnace 10 having end walls 11 and 12 and an opening 13 for admitting parts to be treated and an opening 14 to allow the same parts to leave the furnace. Means for heating the furnace is shown at 16. There are two tracks 18 extending thru the furnace 10 and for a short distance in front of the opening 13 to allow space for a pushing mechanism 65 hereinafter described.

Two ridges 40 extend thru the furnace parallel to and higher than the tracks 18. Legs 24 and 25 support the furnace 10 from the floor, and, supported by the legs 24 is a gear 26 driven by a pinion 28 of a motor 30. The rotation of the gear 26 reciprocates a link 32 coupled to a lever arm 34, fulcrumed at 36, which lever reciprocates a pushing bar 38 on the tracks 18. Work carrying blocks 20 are pushed thru the furnace 10, on the tracks 18 by the pushing bar 38.

In operation, there is placed on each track 18 a carrier block 20 and then a camshaft 22 is placed on these blocks. The movement of 80 the pusher bar 38 forces this assemblage toward the opening 13 of the furnace, and in so doing pushes all the blocks and shafts, in front, into and thru the furnace a distance corresponding to the movement of the 85 bar 38. Upon entering the opening 13 the shafts 22 are lifted from the blocks 20 by the ridges 40. There are vertically extending prongs 21 on the blocks 20 adapted to push the shafts now resting on the ridges 90 40, thru the furnace 10. The forward movement of the shafts thru the furnace on the ridges 40, causes rotation of the shafts.

There are openings 42 thru the floor of the furnace 10 at the discharge end of the 95 tracks 18 so that the carrying blocks 20, after pushing the shafts 22 as far as is necessary, may drop down into chutes 44 and return, by gravity, to the front end of the furnace to be used over again.

A tank 48 containing a tempering liquid is placed beneath the discharge opening 14. Inclined tracks 46 convey the shafts 22 from the opening 14 into the tank 48. A hood 50

surrounding the opening 14 and tracks 46 and extending down below the level of the tempering liquid conducts objectionable fumes from the liquid into the furnace 5 where they are consumed.

It will be understood that the hood 50 closed by the liquid in the tank 48 serves a double purpose of conveying objectionable fumes into the furnace and closing the discharge opening thereof thus acting to retain heat within the furnace. The chutes 44 are tubular in cross section and bolted tightly beneath the openings 42 thus preventing any heat from leaking out at these openings. 10 Therefore the opening 13 is the only opening thru which heat may escape. A furnace of this type is very evenly heated throughout in an economical manner and by causing the shafts 22 to roll, thru the furnace, the heat 15 is very evenly distributed around them.

Obviously various changes may be made in the construction of the furnace and feed mechanism to adapt it to various shapes of objects to be heat treated without departing 25 from the spirit of the invention as described in the preceding specification and claimed in the following claims.

What I claim is:

1. A device of the class described comprising a furnace having receiving and discharging openings, tracks within said furnace, work carrying blocks adapted to slide along said tracks, means for pushing said blocks along the tracks, openings thru the floor of said furnace beneath the discharging ends of said tracks, and chutes beneath said openings adapted to return said blocks to the receiving end of the furnace. 30

2. A device of the class described comprising a heat treating oven having receiving and discharging openings, tracks within said oven, separate work carrying blocks movable along said tracks, means for sliding said blocks along said tracks, ridges within 40 said oven to lift the work from said blocks, means for rolling the work on said ridges, and openings in the floor of said oven beneath the discharge end of said tracks to allow the blocks to fall out of the oven. 45

50 3. A device of the class described, comprising a furnace having a receiving and a discharging opening, tracks within said furnace, separate work carrying blocks adapted

to be pushed thru the furnace along said tracks, ridges parallel to and higher than 55 said tracks and adapted to lift the said work from said blocks, and means for rolling the work on said ridges.

4. A device of the class described, comprising a heat treating oven having a receiving and a discharging opening, tracks extending thru said oven and projecting beyond the receiving opening thereof, work carrying members adapted to slide along said tracks, means on the projected portion 65 of said tracks to push said work carrying members toward the receiving opening of said oven, and means adapted to lift the work from said blocks whereby the work may be rotated while passing thru said 70 furnace.

5. In a device of the class described, a furnace having receiving and discharging openings, tracks extending thru said furnace, work carrying blocks adapted to slide 75 along said tracks, ridges within the furnace and extending along said tracks and acting to lift the work from said blocks, and prongs on said blocks acting to push the work along said ridges. 85

6. A device of the class described comprising a heat treating furnace having receiving and discharge openings, tracks within said furnace, separate work-carrying blocks on said tracks, means for sliding said blocks 90 along said tracks, ridges within said furnace to lift the work from said blocks, means for rolling the work along said ridges, openings beneath the end of said tracks, and means for returning said blocks from said openings 95 to the receiving end of said oven. 100

7. A device of the class described comprising a heat treating oven having receiving and discharging openings, means for receiving articles to be heated and for supporting them outside the oven adjacent the receiving opening aforesaid, and for thereafter moving them thru said oven from the receiving to the discharge opening thereof, and means extending along the oven for lifting the articles being heated from said supporting means as they enter the oven, and for supporting said members while they are being forced thru the oven by said supporting and moving means. 105

THOMAS J. LAURENCE.
